ELECTRODE INSULATOR

Ward W. Watrous, Jr., Chatham, N. J., assignor to Chatham Electronics, Division of Gera Corporation, a corporation of New Jersey

Application September 16, 1955, Serial No. 534,702

1 Claim. (Cl. 313—199)

This invention relates to an electrode insulator for use in gaseous discharge devices. It has particular reference to a structure for insulating and retaining two electrodes within a discharge device which may be subjected to differences of potential which may range up to 10,000 volts.

Many forms of insulators have been used in electron and gaseous discharge devices. In their simplest form these insulators comprise mica washers, mica plates riveted to other electrodes, or to supporting members, and various forms of ceramic blocks. Such prior insulators must generally be assembled and secured to their components before the electrode structure is mounted within the glass envelope. There are frequent occasions, however, when assembly must be made after one or more electrodes have been mounted within the envelope or have otherwise been assembled so as to make the usual assembly quite difficult. The present insulator design permits assembly within an electrode enclosure in a manner which would be exceedingly difficult to perform with the known types of insulators. The insulator further is designed with a shield so as to make sure that gaseous ionization between adjacent electrodes is impossible.

One of the objects of this invention is to provide an improved electrode insulator which avoids one or more of the disadvantages and limitations of prior art arrangements.

Another object of the invention is to permit assembly of one electrode within another electrode without recourse to the usual fastening means.

Another object of the invention is to simplify and improve the construction of electrode assemblies.

Another object of the invention is to provide an electrode insulator which will permit relative movements of two electrodes subjected to unequal heating and cooling cycles.

Another object of the invention is to provide an electrode insulator which is shielded against electrostatic fields which might cause gaseous ionization and current flow.

Another object of the invention is to shield all the junctions between insulator material and conductive shields from electric fields so that there is no tendency for a "cathode spot" to form.

The invention comprises an electrode insulator for slidably mounting two electrodes within the envelope of a gaseous discharge device which contains gas at a reduced pressure and comprises a cylindrical conducting shield which is closed at one end and is secured to a first electrode. A cylindrical insulator is mounted within the shield and is formed with an axial opening. A conducting rod is secured to a second electrode and is adapted to fit into the axial opening. The conducting structures which support the cylindrical shield and the conducting rod are separated by a distance which is less than the mean free path of electrons at the reduced pressure.

For a better understanding of the present invention,

2

together with other and further objects thereof, reference is made to the following description taken in connection with the accompanying drawings.

Fig. 1 is a cross sectional view of a gaseous discharge device showing a portion of the envelope and three electrode insulators mounted between two electrodes.

Fig. 2 is a cross sectional view of the discharge device shown in Fig. 1, taken along line 2—2 of that figure.

10 Referring now to the drawing, an envelope 10 surrounds all the electrodes and contains gas at a reduced pressure. A cylindrical electrode 11 is secured within the envelope and supports a control electrode 12 and a baffle plate 13. Just above the control electrode is an anode 15 which is connected to a positive source of positive potential and is one terminal for the discharge which passes through the tube. The control electrode 12 and the baffle 13 are both conductively joined to the cylindrical electrode 11. A baffle plate 14 is joined to a second cylindrical electrode 16 which is generally connected to a cathode (not shown) and may be connected to ground by means of an external connection.

20 The electrode insulator is shielded by a cylindrical shield 17 which is closed at its bottom end and connected to baffle plate 14 by a flange 18. An insulator 20 is mounted within shield 17 and completely fills the space enclosed by the shield except for an axial opening 21 and a slight chamfer 22 at the open end of the shield. A hole 23 is provided in baffle plate 14 in general alignment with opening 21.

25 The second electrode 13, which in this case is a baffle plate connected to the control electrode 12, is provided with a plurality of conducting rods 24, permanently secured to plate 13 and adapted to fit into the central openings 21 in insulators 20. Rods 24 are long enough to make contact with a major portion of the insulator material but do not extend to the bottom of the opening 21 so that sufficient leeway is provided to permit relative motion between any of the rods and the insulators in which they are positioned due to expansion and contraction of the various metallic electrode materials associated with baffle plates 14 and 13.

30 It should be noted that cylinders 11 and 16 are spaced at a distance which may be small in relation to the mean free path of electrons in the gas at the reduced pressure in the envelope. It is also evident that baffle plates 13 and 14 are within the same distance and nowhere within the geometry of the insulator is there sufficient length for an electron to cause ionization which will result in an arc or glow discharge. Shield 17 effectively shields the rod 24 from any electrostatic field which might be present due to other electrodes placed within the walls of cylinder 16. The hole 21 may, under some conditions, extend through the entire insulator 20.

35 55 When the parts are assembled, cylinder 11 is first secured within the envelope in proper spaced relation to the anode 15 and anchored by means not shown in the drawings. Then cylinder 16 is pushed into cylinder 11 and adjusted so that rods 24 fit into openings 21. After being adjusted for proper spacing between plates 13 and 14, the lower portion of cylinder 16 is anchored, and the tube is ready to be finished and exhausted.

40 60 65 While there have been described and illustrated specific embodiments of the electrode insulator, it will be obvious that various changes and modifications in the materials and in the relative dimensions can be made therein without departing from the field of the invention which should be limited only by the scope of the appended claim.

I claim:

An electrode insulator for slidably mounting two electrodes within the envelope of a gaseous discharge tube

which contains gas at a reduced pressure comprising, a cylindrical conducting shield closed at one end and secured to a first electrode, an insulator mounted within said shield and having a central axial opening, a conducting rod secured to a second electrode and fitting into said axial opening, and conducting structures connected to said first and second electrodes which are separated by a distance which is less than the mean free path of electrons at said reduced pressure.
